(57) **CLAIM**

The ornamental design for an oval bottle, as shown and described.

DESCRIPTION

FIG. 1 is a perspective view of a bottle showing my new design;

FIG. 2 is a front view thereof;

FIG. 3 is a right side view thereof;

FIG. 4 is a bottom plan view thereof; and,

FIG. 5 is a top plan view thereof.

The broken lines shown in FIGS. 1–3 are for illustrative purposes only and form no part of the claimed design.
